USPC D6/553, 653.1, 657, 660–661,

CLAIM

The ornamental design for a modular wall incorporating recessed, extendable furniture, as shown and described.

DESCRIPTION

D6/662–662.1, 663, 664, 671, 671.1, 672,

FIG. 1 is a perspective view of a modular wall incorporating recessed, extendable furniture showing the design;

D6/705; D25/3

FIG. 2 is another perspective view thereof showing a door of the recessed, extendable furniture in an opened position;

CPC A47B 5/04; A47B 17/03; A47B 17/04;

FIG. 3 is a front elevational view thereof;

A47B 46/005; A47B 96/00; A47F 3/00;

FIG. 4 is a front elevational view thereof showing the door of the recessed, extendable furniture in the opened position;

A47F 3/005; A47F 3/06; E04B 2/745; E04B

FIG. 5 is a right elevational view thereof;

2/7416; E04B 2/7424; E04B 2/7425; E04B

FIG. 6 is a left elevational view thereof;

2/7435; E04F 13/081

FIG. 7 is a top plan view thereof; and,

FIG. 8 is a bottom plan view thereof.

The broken lines are for illustrative purposes only and form no part of the claimed design.

1 Claim, 6 Drawing Sheets

See application file for complete search history.
